CLAIM

(21) Appl. No.: **29/271,076**

The ornamental design for a surgical tissue stimulator/locator, as shown and described.

(22) Filed: **Jan. 9, 2007**

DESCRIPTION

(51) **LOC (8) Cl.** 24-02

FIG. 1 is a perspective view of a surgical tissue stimulator/locator showing my new design;

(52) **U.S. Cl.** D24/133; D24/144

FIG. 2 is a left side elevation view thereof; the right side elevation view being a mirror image thereto;

(58) **Field of Classification Search** D24/133,

FIG. 3 is a top plan view thereof;

D24/144, 147; 600/554, 552, 556, 557; D19/41,
D19/16, 51

FIG. 4 is a bottom plan view thereof;

See application file for complete search history.

FIG. 5 is a front elevation view thereof; and,

FIG. 6 is a rear elevation view thereof.

The broken lines showing in FIGS. 1–6 are for illustrative purposes only and form no part of the claimed design.
